LOUIS ZIEGLER, OF IRVINGTON, NEW JERSEY, ASSIGNOR TO CONSOLIDATED FIREWORKS COMPANY OF AMERICA, OF NEW YORK, N. Y., A CORPORATION OF NEW YORK.

TOY PISTOL.

1,265,862.

Specification of Letters Patent. Patented May 14, 1918.

Application filed August 19, 1916. Serial No. 115,771.

To all whom it may concern:

Be it known that I, LOUIS ZIEGLER, a citizen of the United States, and a resident of Irvington, county of Essex, and State of New Jersey, have invented certain new and useful Improvements in Toy Pistols, of which the following is a specification.

My invention relates to toy pistols of the magazine type and particularly to such pistols designed for exploding explosive charges contained in a coiled cap tape which is unrolled as it is used up.

An object of the invention is the provision of simple apparatus which will continuously perform all the various functions of automatically feeding forward the tape, cocking the hammer and firing by merely pressing repeatedly upon the trigger.

Another object of the invention is the provision of novel means whereby the magazine can readily be opened and recharged, and when closed the explosive material will be thoroughly inclosed and protected.

Another object of the invention is the provision of means whereby a single element, rotated always in the same direction, serves the function of feeding the tape forward and also of cocking the hammer and freeing it for firing, the tape being fed forward when the hammer is lifted off of it and it is free to be fed forward to present a new charge for firing.

Other objects of the invention will appear in connection with my detailed description. With the foregoing and related objects in view, my invention consists in the improvement of devices of the character named in numerous important particulars and in the improvements, parts and combinations hereinafter set forth and claimed.

In the accompanying drawing forming a part of this specification, and wherein the same reference characters are uniformly applied to designate the same parts throughout, I have illustrated, for the purpose of making my invention clearly understood, one form of device in which the invention may be embodied.

In the said drawing Figure 1 is a side elevational view of one half the pistol shell

and showing the inclosed working parts and their relation to one another. Fig. 2 is a similar view of the remaining side of the pistol shell. Fig. 3 is a horizontal cross-sectional view taken substantially on line 3—3, Fig. 1. Fig. 4 is a view partly in perspective and partly in cross section of the starwheel which feeds the tape and actuates the hammer, and Fig. 5 is a detail perspective view of the trigger.

The main half frame or shell in which the operative parts are preferably mounted is designated by the reference numeral 10 and the remaining half by the reference numeral 11. It is not, of course, essential that the shell of the pistol be made up of such two parts, but this is the preferred construction. When the shell is so constructed the parts may be secured together by a screw 12 passing through an opening 13 in the part 11 and screwed into a threaded opening 14 in the part 10. A magazine chamber 15 is provided to receive the tape 16 containing the explosive charges, and access to such chamber, for reloading the pistol when the magazine is empty, is had through the upper side thereof, such opening being ordinarily closed by the swinging member 17 comprising the anvil block 18 and having a downwardly extending portion 19 which is pivoted in the shell at 20. Said member is held in its depressed or closed position by suitable spring means, and the same may comprise a plunger 21 having a head 22 engaging the member 17, and between which head and the end of the pistol barrel there is the spring 23. The plunger 21 is encircled by the spring 23 and may extend through a guide aperture 24 in the end of the barrel and thereby serve to give the suggestion of a projectile protruding from the end of the barrel, as shown in Fig. 1. The anvil face 25, against which the charge is detonated, is formed on the rear end of the member 17, and a projecting roughened thumb piece 26 may be provided for convenience in manipulation.

The hammer 27 is pivoted at 28 and the charge is exploded by the striking of its face 29 upon the coacting face 25 of the

anvil block. The hammer is urged forward by a spring as 30. The forward side of the hammer member 27 is provided with two projections or lugs 31 and 32. The lug 31 serves to guide the tape 16' between the striking surfaces 29 and 25, and to prevent the tape catching on or under the hammer, and the other lug 32 serves the function of a cam in co-operation with the starwheel 33 and also as a stop to prevent backward turning of the starwheel. Said starwheel is pivoted at 34 and has extending prongs 35 here shown as five in number. The starwheel 33 is turned on its pivot, in the direction of the arrow in Fig. 1, by the operation of the trigger and each of the prongs 35 serves in turn, as the same is rotated, by co-action with the face 32' of the lug 32, to force back the hammer 27 against the spring 30, and when the point 32'' has been passed the hammer is driven forward by the spring 30 and strikes the hammer block 25, thereby exploding any charge or cap in or on the tape 16 which may be presented between these surfaces. The starwheel 33 also serves to feed the tape, and for this purpose the points of the prongs 35 project through the rear wall of the recess or magazine compartment 15 and come close to or in contact with the arcuate surface 36 on the rear lower face of the anvil block 17 so that the free end of the tape 16' passes between the prongs of the starwheel and said surface 36, and the tape is moved outward and unwound from the coil upon the rotation of the starwheel 33, thereby presenting new surfaces for succeeding blows of the hammer.

The trigger 37 is pivoted at 38 and the spring 39 serves to hold the same normally in substantially the position shown in Fig. 1, opposing backward movement of the trigger 37, which may be caused by pressing on the same with the finger. The upper end 40 of the trigger is provided with means for turning the starwheel 33 in a clockwise direction and for permitting it to slip past the same when returned to normal position so as to engage with another prong of the starwheel and to impart further rotation thereto. In the construction shown, the upper end 40 of the trigger 37 is provided with a lateral extension 41 having a square front face 42 with a lip 43 and with a laterally inclined rear surface 44, the front surface 42 serving to engage with and advance the prongs of the starwheel 33 as the trigger is actuated, and the inclined surface 44 serving to carry the trigger backward over the next prong so that the same may be engaged for further actuation upon the next movement of the trigger. The hammer itself serves as a pawl for preventing reverse movement of the starwheel 33 by en-

gagement of each prong with the lower 65 face 32' of the lug 32 after passing the point 32''. The end 40 of the trigger 37 is held lightly and resiliently toward the starwheel 70 75 80 85 90 95 100 105 110 115 120 125 130 135 140 145 150 155 160 165 170 175 180 185 190 195 198 200 202 204 206 the invention may be simply and cheaply constructed, that the number of moving parts is very small, and that each part performs its manifold functions with certainty, 5 that the magazine is well protected so as to avoid all danger of premature explosion, and that a very safe and attractive toy is provided which, without subjecting the operator or others to danger, nevertheless acquaints the operator fully with the use of 10 automatic pistols of the ordinary and well known types.

It will be understood that the embodiment of my invention selected for illustration is intended only for the purpose of affording a clear understanding of the invention and that I am not to be restricted to such specific form, but that numerous departures therefrom and changes therein may 15 be resorted to within the scope of my claims and without departing from my invention or sacrificing any of its advantages.

Having thus described my invention, I claim:

25 1. In a pistol, a magazine for cap tape, said magazine opening upwardly, a member serving as a closure for said magazine and also as an anvil block, said member being provided with a downward extension, said 30 extension being pivoted within the magazine, and a spring acting upon said member above the pivot and serving to hold said member in position to close the magazine.

2. In a pistol, a magazine chamber for 35 cap tape, said magazine being open on its upper side, a member fitting in said opening and having a downward extension by which it is pivoted within the magazine, a plunger in the pistol barrel adapted to engage said 40 member, and a spring about said plunger and adapted to press the plunger into engagement with the closure member so as to hold it in position to close the magazine and to present the end thereof as an anvil block.

45 3. In a pistol, a magazine for cap tape open on its upper side, a starwheel mounted for rotation and having its prongs extending into contact with the tape for advancing the same, a spring-depressed closure for said 50 magazine, said closure means serving to hold the cap tape in contact with the starwheel prongs, and also serving the additional functions of an anvil block and a guide for the cap tape, and trigger means for rotating the starwheel step by step.

55 4. In a pistol, a magazine for cap tape open on its upper side, a hammer, a starwheel mounted for rotation and having its prongs extending into contact with the tape for advancing the same, said prongs serving 60 also for operating the hammer, a spring-depressed closure for said magazine, said closure means serving to hold the cap tape in contact with the starwheel prongs, and

also serving the additional functions of an 65 anvil block and a guide for the cap tape, and trigger means for rotating the starwheel step by step.

5. In a pistol, a starwheel mounted for rotation, a hammer, a lug on the hammer 70 extending into the path of the starwheel, a trigger having an upward extension in the path of the prongs of the starwheel, and means whereby the movement of the trigger serves to impart step by step rotation to the 75 starwheel engaging a prong thereof when moved in one direction and moving past the prongs thereof when moved in the opposite direction.

6. In a pistol, a magazine for cap tape, a 80 hammer, starwheel for advancing the cap tape and also operating the hammer, and a guide on the hammer for the cap tape.

7. In a pistol, a starwheel having its 85 prongs notched out on a side thereof, a trigger having means to engage said prongs and rotate said starwheel step by step, said trigger being adapted to ride over the notched out portion of the starwheel prongs when moved backward.

8. In a pistol, a starwheel, a hammer, means on the hammer whereby rotation of the starwheel actuates the hammer, a trigger adapted to rotate said starwheel step by step in one direction, and spring means for 95 pressing said trigger yielding into engagement with said starwheel, whereby the trigger may retreat past the prongs of the starwheel.

9. In a pistol, a magazine for cap tape, a 100 starwheel mounted for rotation and having its prongs extending into contact with the cap tape so as to advance the same, a hammer having a projection extending into the path of the prongs of the starwheel whereby 105 the hammer is actuated from the starwheel and the starwheel held from retrograde movement, said hammer having a second projection serving as a guide for the cap tape, and trigger actuated means for im- 110 parting step by step rotation to said starwheel.

10. In a pistol, a magazine for cap tape open on its upper side, a starwheel mounted for rotation and having its prongs extending into contact with the tape for advancing the same, and a spring-depressed closure for 115 said magazine, said closure means serving to hold the cap tape in contact with the starwheel prongs, and trigger means for rotating 120 the starwheel step by step.

11. In a pistol, a starwheel mounted for rotation, a magazine for cap tape presenting the tape in proximity to the starwheel, a spring-depressed closure for said magazine 125 serving to guide said cap tape and to hold it in contact with the prongs of the starwheel, a hammer, a projection on the ham-

mer extending into the path of the starwheel prongs whereby the hammer is actuated by the starwheel, said hammer having a second projection serving as a guide for the cap tape, the starwheel prongs being rounded out on one edge, a pivoted trigger having means to engage said starwheel prongs when the trigger is pressed and hav-

ing an inclined surface to ride over the cut out portion of the starwheel as the trigger is returned, and means for resiliently pressing said trigger toward the said starwheel.

In testimony that I claim the foregoing, I have hereto set my hand, this 28th day of July, 1916.

LOUIS ZIEGLER.
